UNITED STATES PATENT OFFICE.

NEAL LARKIN ANDERSON, OF WINSTON, NORTH CAROLINA.

TYPE-WRITER CARRIAGE-RETURN MECHANISM.

1,067,635.

Specification of Letters Patent. Patented July 15, 1913.

Application filed November 3, 1910. Serial No. 590,474.

To all whom it may concern:

Be it known that I, NEAL L. ANDERSON, a citizen of the United States, residing at Winston, county of Forsyth, North Carolina, and whose post-office address is First Presbyterian Church, Winston-Salem, North Carolina, have invented certain new and useful Improvements in Type-Writer Carriage-Return Mechanism; and I do hereby declare the following to be a full, clear, and exact description of the invention, such as will enable others skilled in the art to which it appertains to make and use the same.

The invention relates particularly to the application of power-driven carriage-return mechanism to typewriters of that type which, like the Underwood typewriter, for example, have a laterally moving line-spacing lever through which the power of the carriage-return mechanism is applied to space the line and return the carriage. In my earlier U. S. Letters Patent No. 900,642 of October 6, 1908, and No. 953,938 of April 5, 1910, I have disclosed improved power-driven carriage-return mechanism applicable to typewriters of this character, and the present invention has been developed with the particular purpose of improving the operation of such carriage-return mechanism. It may, however, be employed with other types of carriage-return mechanism, and although in my earlier patents the whole power of the carriage-return mechanism was applied to the typewriter carriage through the line spacing lever, that is not essential to the present invention.

I have found that when the carriage-return cord or band is attached directly to the line-spacing lever, and particularly where there is some tension at all times on the said band, the tendency is to interfere with the proper operation of the line-spacing lever. As is well known, the line-spacing operation is ordinarily brought about by the engagement of a pawl with a ratchet on the axle of the platen, the pawl being actuated by the line-spacing lever, and mechanism being provided for adjusting the period of engagement of the pawl to change the line-spacing movement. The operation of the line-spacing lever is such that during the first part of the movement the pawl is out of engagement with the ratchet, and the resistance of the platen is not opposed to the movement of the lever, and the time at which the pawl comes into engagement with

the ratchet depends upon the setting of the adjusting mechanism. If then the carriage-return band is fastened directly to the line-spacing lever and there is some tension on the band, as should preferably be the case, the lever is likely to move under the pull of the band until it is opposed by the engagement of the pawl with the ratchet on the platen. The result is that if the line spacing is changed from a narrow to a wider space, the band will not permit the ratchet to move back far enough to effect the new spacing, but will hold it in the forward position where it effects only the narrow spacing. Furthermore, it is best, in order to insure the even and regular spacing of the paper, to move the platen by a relatively sharp blow, taking advantage, for that purpose, of the momentum acquired by the line-spacing lever and associated parts during the first part of the movement, before the pawl engages the ratchet, and if this preliminary movement is prevented by the tension of the band, the feeding of the paper is likely to be defective.

In accordance with the present invention, therefore, I do away with the connection of the carriage-return band to the line-spacing lever, and connect it to the carriage, and in order to effect by means of the power-driven carriage-return mechanism, the return of the carriage and the spacing of the platen, I provide a sliding abutment which is actuated by the pull of the carriage-return band to deliver, during the return movement, a sharp blow to the line spacing lever. Inasmuch as, in typewriters of the character referred to, the line-spacing lever is the thing through which power is applied by hand, in the ordinary operation of such machines, to return the carriage, and inasmuch as there is provided on the carriage, for that purpose, a fixed abutment against which the line-spacing lever strikes at the end of the line-spacing movement, to afterward impart the force applied to it directly to the carriage, it becomes convenient, in accordance with the preferred form of my invention, to apply the force of the power-driven carriage-return mechanism, just as the hand power is usually applied, *i. e.*, to first sharply move the line-spacing lever to effect the line-spacing operation, and then to apply the carriage-return power to the carriage through the line-spacing lever and its fixed abutment. This desirable result

may be effected, in accordance with my invention, and the line-spacing and carriage-return movement under the power of the carriage-return mechanism may be made to correspond exactly with the normal intended movement when the carriage is returned by hand, by fastening to the frame of the carriage a slide to which the carriage-return band is connected, and providing on the slide an abutment adapted to strike and actuate the line-spacing lever, the slide being connected to the carriage by a spring which is of sufficient strength to withdraw the abutment out of engagement with the line-spacing lever, against that tension which is normally on the carriage return cord when the carriage is advancing or at rest. Such preferred form of the invention is illustrated in the accompanying drawings, in which—

Figure 1, is a front elevation, of a somewhat diagrammatic character, of an Underwood typewriter equipped with the power-driven carriage-return mechanism disclosed in my above mentioned patents, together with the improved mechanism of the present invention for applying the power to the carriage; Fig. 2, is a detail plan partly in section, and on a larger scale, showing the slide in its relation to the line-spacing lever; and Fig. 3 is a section on the line 3—3 of Fig. 2.

In the drawings, 1 represents the frame of the typewriter, 2 the casing of the carriage return motor, 3 the pulley on which the carriage return band 4 is wound, and 5 a spring pressed arm forming part of an automatic slack take-up mechanism constructed in accordance with my Patent No. 953,938, and which puts some tension on the carriage-return band 4. The carriage return keys, which control the motor, are shown at 6 and 7. The band 4 runs over the guide pulley 8 journaled in a bracket on the frame of the machine and its free end is passed over the hook 9 on the slide bar 10, which slide bar is guided in and supported by the guide member 11 fastened to the front bar of the typewriter carriage by the screws 12. Extending from the guide member 11 beneath the front bar of the carriage is a short arm 14, and between this arm and a rearwardly extended arm 15 fixed to the slide bar 10 is a coiled spring 16, which tends to draw the slide bar to the left against that tension which is normally on the carriage-return cord when the carriage is not being returned. At the extreme left-hand end of the slide bar 10 is an upstanding abutment 17 adapted to engage the line-spacing lever 18, and the line-spacing lever is limited in its movement, in the usual way, by the abutments 19 and 20.

The operation will be readily understood.

When the power - driven carriage - return mechanism is at rest the tension of spring 16 is sufficient to hold the slide bar 10 in its extreme left hand position. Upon the application of power to return the carriage, the spring 16 yields, permitting the abutment 17 to strike and sharply move the line-spacing lever to space the platen, and at the end of the line-spacing movement the lever comes against the abutment 19 and thereafter the force of the power - driven carriage-return mechanism is applied to the carriage through the line-spacing lever 18, and the abutment 19, and to some extent through the spring 16. It will be observed that though in the preferred form the power used in returning the carriage is thus applied to the carriage through the line-spacing lever 18, since this is a convenient arrangement in the Underwood typewriter, yet the parts may be so arranged, by limiting in any way the expansion of the spring 16, as to apply the power to the carriage through the spring or through the limiting stop, after the line-spacing lever has been moved to effect the line-spacing operation.

What I claim is:

1. A typewriter carriage return mechanism including a laterally moving line-spacing lever and a carriage return motor, in combination with a device actuated by the pull of the carriage return motor to strike and actuate the line-spacing lever; substantially as described.

2. A typewriter carriage return mechanism including a carriage return motor and a laterally moving line-spacing lever normally disconnected from said motor, in combination with a device actuated by the pull of the carriage return motor to automatically apply that pull to the line-spacing lever and thereby space the platen and return the carriage; substantially as described.

3. A typewriter carriage return mechanism including a laterally moving line-spacing lever and a carriage return motor, in combination with a slide on the carriage to which the motor is connected, an abutment on the slide adapted to engage and actuate the line-spacing lever, and a spring tending to draw the slide away from the line-spacing lever; substantially as described.

4. A typewriter carriage return mechanism including a laterally moving line-spacing lever and a carriage return motor, in combination with a slide bar, a carriage return band connected at one end to the motor and at the other end to the slide bar, a guide-way for the slide bar secured to the carriage, an abutment on the slide bar adapted to engage the line-spacing lever, and a spring tending to draw the slide bar away from the line-spacing lever; substantially as described.

5. A typewriter carriage return mecha-

nism including a laterally moving line-spacing lever and a carriage return motor, in combination with a slide bar, a hook on said bar, a carriage return band connected 5 at one end to the motor and at the other end to the hook, a guide-way for the slide bar fastened to the front bar of the carriage, a short arm extending from said guide-way beneath the said front bar, a short arm 10 tending from the slide bar beneath the said front bar, a spring connecting said arms, and an abutment on the slide bar adapted to engage and actuate the line-spacing lever; substantially as described.

In testimony whereof I affix my signature, 15
in presence of two witnesses.
